UNITED STATES PATENT OFFICE.

EDMUND LAND AND FRANK L. FISHER, OF GRAND RAPIDS, MICHIGAN, ASSIGNEES, BY
MESNE ASSIGNMENTS, TO FREDERICK C. STEVENS, OF ATTICA, NEW YORK.

TELEPHONE SYSTEM.

1,117,407.

Specification of Letters Patent. Patented Nov. 17, 1914.

Application filed March 22, 1906. Serial No. 307,318.

To all whom it may concern:

Be it known that we, EDMUND LAND, a subject of the King of Great Britain, and FRANK L. FISHER, a citizen of the United States of America, residents of Grand Rapids, county of Kent, and State of Michigan, have invented a new and useful Improvement in Telephone Systems, of which the following is a specification.

10 Our invention pertains to the automatic distribution of telephone calls coming into a central office, its function being that duty known as "Y-switching". By Y-switching is meant the distribution of calls from telephone lines to a switchboard where the calls are to be completed, a Y-operator in manual practice having no communication with the patrons calling, but merely passing the calls to a switchboard operator, or "A-operator" 15 for attention. The object is to distribute the incoming calls properly among the A-operators so that the total task of answering all calls may be distributed evenly throughout the line-connecting-board, or "A-board". 20 This accomplishes an improvement in the quality of the service given by the switchboard as a whole, or a decrease in the cost of giving service, or both. The mechanical requirements, therefore, of Y-switching, cover 25 the distribution of calls from a large number of telephone lines to a smaller number of trunk lines, a calling line being connected to an idle trunk line and left in connection with that trunk until the call is completed. 30 Our invention consists of a system whereby the Y-switching is done automatically, a group of trunks being assigned to a group of subscribers' lines and automatic switches according to our invention provided for 35 connecting a calling line to an idle trunk, with the result that any calling line is connected to the first idle trunk line encountered by the operation and left connected to that trunk until the call is completed, both 40 45 the trunk line and the subscriber's line being so guarded by busy test conditions that neither is interrupted during the continuance of the connection for conversation.

The advance in our invention over the 50 previous state of the art is that a Y-switch per trunk is provided instead of a Y-switch per line; inasmuch as the number of trunks always is smaller than the number of lines, a resultant economy is effected.

55 Three figures accompany this specifica-

tion, of which Figure 1, drawn on two sheets, Fig. 1^a and Fig. 1^b, respectively, show the circuits of the system; Fig. 2 shows assembly of a switch adapted to the requirements of our system, and Fig. 3 shows the 60 rotary shaft of the switch of Fig. 2.

It will be seen by Figs. 2 and 3, that 1 is a bank of fixed contacts in three layers, each layer being substantially a complete circle with fixed contacts equally spaced 65 throughout the circle the entire bank thus presenting a cylindrical inner surface from which the fixed contacts project; concentric with this cylindrical surface is the shaft 2, upon which is mounted the ratchet 3, having a number of teeth equal to the number of contact intervals in the bank of fixed contacts. A magnet 4 with armature 5 and pawl 6 is also so disposed that the pawl engages the ratchet 3 and at each attraction 70 of the armature 5 the ratchet 3 is stepped forward one step. Radial contacts 7, 8, 9 are attached to the shaft, insulated from the shaft and from each other, these radial contacts being so designed that they are in 75 contact respectively with the homologous fixed contacts of the three layers, and step from contact to contact in the layers as the ratchet 3 is set forward step by step by the action of the magnet 4. Contact rings 10, 11, 12, are mounted upon the shaft 2, insulated from each other and from the shaft, and are connected respectively to the radial contacts. Fixed brushes 13, 14, 15, bear 80 upon these contact rings, and thus electrical connection is made between the fixed parts 13, 14, 15 and the moving parts 7, 8, 9. For convenience in reference, the fixed contacts, as 16, 16, 16, 16, may be referred to as waiting contacts; the radial contacts 7, 8, 9, as 85 wipers, and the magnet 4 as a motor magnet. In the circuit drawing, Fig. 1^b, we have shown diagrammatically three such Y-switches, the respective parts being labeled 90 to correspond with the labels given in Figs. 2 and 3. The banks of waiting contacts are 1, 1', 1'', the individual contact points not being labeled; the shafts, brushes and contact rings are omitted from the diagram as 95 unnecessary detail, the conductor wires being shown connected directly to the wipers, 7, 8, 9, 7', 8', 9', 7'', 8'', 9''; the magnets are shown at 4, 4', 4''; armatures are shown at 5, 5', 5'', but the pawls 6 and ratchet 3 are 100 omitted as unnecessary to the diagram; the 105 110

back contact of the magnet armature is shown at 17, 17', 17''. Each of the Y-switches has associated with it an auxiliary relay 18, 18', 18''.

- 5 In Fig. 1^b we have shown three complete trunk equipments, V, W, and X, each trunk equipment consisting of a Y-switch and auxiliary relay as described above, a pair of condensers 19, 20, a pair of visual signals 21, 22, a listening key 23, to which an operator's telephone set is attached in the usual manner, a ringing key 24, to which a ringing generator is attached at the outer contacts in the usual manner, and a connecting plug 10 25. Any required number of similar trunks may be provided in any installation. The number of lines served by a single trunk will be limited by the number of contacts in a layer of waiting contacts. If this number 20 were 100, there would be required a ratchet wheel of 100 teeth.

In Fig. 1^a, we have shown the equipment of four lines, including the relay equipment which pertains to the lines, and also the 25 multiple terminal equipment, the latter pertaining to jacks for manual connection at the connecting switchboard, as well as to waiting contacts for automatic connection with Y-switches. Taking for example, line 30 A; a line relay 26 and cutoff relay 27 provided at A', the line thence extending into the multiple cables to which are attached a plurality of calling jacks, as A², A³, and also waiting contacts in a plurality of Y-switches, as V, W, X. It is to be noted that one of the line-wires is normally interrupted at a contact of a relay, for example 35 27; but this is closed when a call is instituted. The trunk plugs 25, 25', etc., are 40 adapted to connect with the calling jacks A², B², etc., and the operator's circuit used shall be adapted to detect a busy test upon the multiple jacks in some convenient well known way.

- 45 In Fig. 1, a conductor is shown in double-dotted lines, constituting conductors 28, 28', 28², 28³, 29, 29', 29², 29³, 30, 31, 32, 32', and 32'', all of which conductors are concerned in the function of selecting the next idle 50 trunk and in causing that trunk to become active in selecting a calling line in the following manner: It will be noted that the entire Fig. 1 does not show a closed battery circuit; all movable parts are in their respective positions of rest. It will be noted that the double-dotted conductor 31 extends in multiple branches to all of the line equipments, A', B', C', D', and is separated from ground at those points by open relay contacts; also, that it extends in series through the trunk equipments V, W, X, being connected to ground through a magnet coil and a battery in the first of the trunk equipments. If, now, a patron at substation A⁴ 55 takes the receiver from the hook of a telephone set of the usual central battery type circuit will be closed from grounded battery through 33, 26, 34, 35, A⁴, 36, 37, ground, energizing relay 26, and closing a circuit as follows: from grounded battery through 17, 70 5, 38, 4, 39, 31, 29, 28, 37, ground, energizing motor-magnet 4 and stepping forward wipers 7, 8, 9; this circuit by energization of motor-magnet 4 breaks itself at 17, and thus the armature 5 of the motor magnet 75 vibrates and advances the wipers 7, 8, 9, by steps until a circuit is found to interrupt the circuit over conductor 31, above described, which occurs when the wipers reach the calling line; at that time wiper 8 contacts with conductor 40, which extends to the armature of energized relay 26, and the circuit is found as follows: from grounded battery through 17, 5, 38, 4, 41, 42, 18, 43, 21, 44, 45, 8, 40, 46, 27, ground; this it will be noted 80 gives current through the windings of relays 4, 18 and 27 and through the winding of visual signal 21, the adjustment of relays 18 and 27 and the adjustment of visual signal 21 being such that these relays and that signal are energized and operated. The adjustment of relay 4 however is such that the current through conductor 41, reduced as it is by the resistance of the three series windings in elements 18, 21 and 27, is insufficient 85 90 to overcome the armature tensions, and inasmuch as the operation of the armatures of relay 18 has interrupted the path through the conductor 39, the relay 4, which is the motor magnet of the device, does not attract 95 100 its armature and remains inactive and the contact between its armature and the contact 17 remains closed. By the operation of relay 18, the circuit through conductor 39 to conductor 31 is broken, and the Y-switch of trunk equipment V stops with its 105 trunk conductors in connection with the conductors of the multiple pertaining to line A. By the energization of cut-off relay 27, the conductor 36 is connected to the conductor 46 and thus to conductor 40 and thus to the multiple of the line and to the trunk conductors through the contact 46 and 40; thus a new circuit is formed for the line conductors 35 and 36, the return to ground 110 being now through the winding of relay 27 instead of through conductor 37 as was the case while waiting for the action of the Y-switch. By the operation of the lower armature of relay 18, ground is connected 115 through conductors 47, 48, 7, 49, 50 to the test rings of the jacks A², A³, thus preventing the line from being taken by an operator with a connecting plug. The calling line A, now is connected to manual switching means, such as the plug 25, situated before a telephone operator at a manual switchboard, and the visual signal, 21, associated with that plug, is energized to attract the attention of the operator; the 120 125 130

operator then answers the call, using her listening key 23' in the usual manner, and completes the connection as requested by the patron, and in any manner provided for in manual switchboards. If the line called for be, say, the line D, the plug 25 may be inserted into any multiple jack, as D³, of that line, placing the busy test condition of ground upon the test ring of all multiple jacks as well as upon the waiting contacts associated with that line; the signal bell at the substation then may be rung by the ringing key 24, the circuit being from grounded generator through tip of plug and over the line, back to ground at conductor 37³. Upon the answering of the called station, relay 26³ is energized, closing circuit from grounded battery through 22, 51, 52, 53, 25, D³, 54, 55, 27³, 56, ground, energizing visual signal 22 to indicate to the operator that the called patron has answered. This results also in the energization of relay 27³, giving proper talking conditions to the called line. It will be noted also that the operation of the upper armature of the relay 18 has connected the conductor 31 to conductor 32, thereby extending that conductor into the Y-switch of trunk equipment W, where the double-dotted conductor system now finds grounded battery through a winding of the motor-magnet of the Y-switch of trunk equipment W. Trunk equipment W, therefore, is the next trunk equipment in order for use, and it will respond to the call of the next calling telephone line.

In connection with the diagrammatic representation of the Y-switch of trunk equipment W, it will be noted that the wipers 7', 8', 9', rest upon the waiting contacts of line C; this is merely incidental, and would result from the use of the trunk by line C and no subsequent use of either the trunk or the line. The trunk wipers have no release or restoring mechanisms, and have no predetermined normal position of rest, remaining wherever they happen to be left after a conversation until required for use elsewhere, or until the line upon which they are resting becomes busy.

Assume now that line B calls, relay 26' will be energized and motor circuit completed from grounded battery through 17', 5', 38', 4', 39', 32, 31, 30, 29', 28', 37', ground; at the first step of the wipers 7', 8', 9', they will engage the busy line D, when three circuits will be completed upon release of armature 5' as follows: First circuit extends from grounded battery through 17', 5', 38', 4', 39', 32, 31, 30, 29', 28', 37', ground; second circuit extends from grounded battery through 17', 5', 38', 4', 41', 57', 48', 7', 58, 59, D³, 25, 60, ground; third circuit extends from grounded battery through 17', 5', 38', 4', 41', 42', 18', 65, 21', 44', 45', 8', 61, 62, 54, 55, 27³, 56, ground.

If, through this third circuit the relay 18' were energized to operate, the Y-switch of trunk equipment W would stop upon this busy line, but the current through that relay is very small owing to the fact that it is shunted by two other circuits involving relay 27³ as parts thereof, viz: from grounded battery through 22, 51, 52, 53, 25, D³, 54, 55, 27³, 56, ground, and from grounded battery through 26³, 35³, substation, 36³, 27³, 56; the current flow through relay 18' therefore is insufficient to energize it to operate, and motor magnet 4' is operated by the combined currents through the two circuits, "first circuit" and "second circuit", above described, thus passing the trunk wipers over the busy line's waiting contacts. The wipers so pass on around the switch, passing line A in manner similar to the manner in which line D was passed, the difference being that line A is busy because it had called and line D is busy because it was called. The circuits involved are as follows: First circuit exactly as above described as to D; second circuit extends from grounded battery through 17', 5', 38', 4', 41', 57', 48', 7', 49', 50, 49, 7, 48, 47, ground; third circuit extends from grounded battery through 17', 5', 38', 4', 41', 42', 18', 43', 21, 44, 45, 8, 40, 46, 27, ground, and from grounded battery through 33, 26, 34, 35, A⁴, 36, 27, ground; thus both classes of busy lines are passed, and the Y-switch of trunk equipment will stop in connection with the terminals of the calling line B, and by energizing the relay 18' will connect the double-dotted conductor to link conductor 32', thereby providing a circuit extending from grounded battery through 17'', 5'', 38'', 4'', 39'', 32', 32, 31, and thence branching to all line equipments, whereby it is seen that the next calling line will cause trunk X equipment to operate and to care for the call in the manner already described for trunk equipments V and W.

When the calling subscriber, as at substation A⁴, hangs up his telephone, relay 26 will be released, breaking the circuit which energizes relay 18, and by the release of relay 18 the connection between the motor magnet and the double-dotted system of conductors will be restored, so that trunk V will take the next incoming call regardless of the condition of busyness or idleness of trunk equipments V or W or others.

It has been noted that trunk equipment W has its wipers resting upon the waiting contacts of line C; if, now, line C becomes busy by being plugged into at one of its multiple jacks, the condition of busy test will be manifest by a ground upon its test

conductors and therefore upon the waiting contact with which wiper 7' is in contact; this will ground 7' and give circuit as follows: from grounded battery through 17', 5', 38', 4', 41', 57', 48', 7' ground energizing motor magnet 4', and stepping the trunk wipers off of the now busy line; if the next line be busy a ground will be encountered by wiper 7', and the vibration of motor 10 magnet 4' will continue until wiper 7' finds a waiting contact not grounded, where it will wait until moved, either by reason of the line contacted with becoming busy or by reason of the trunk itself being required to care for an incoming call. In case a second call is made by a given line, while the trunk equipment W still has its wipers resting on the waiting contacts of that line, that trunk equipment will operate in the previously described manner, except that it will not rotate, but will immediately signal the operator and establish busy conditions. The plugs, 25, 25', 25'', may be in the same central office with the jacks A², B², etc., or they may 20 be in separate central offices or may be located at separate switchboards.

We have thus described fully our system of automatic Y-switching, and its manner of operating; we do not wish to limit ourselves 30 in all particulars to the details herein shown and described, as we know that many modifications and variations may be devised without departing from the spirit and scope of our invention.

35 What we claim as new and desire to secure by United States Letters Patent is:

1. In a telephone system, a plurality of telephone lines, multiple jacks forming multiplied terminals for said telephone lines, 40 trunks, Y-switches associated with said trunks, sets of waiting contacts in said Y-switches forming additional multiplied terminals for said telephone lines in multiple with the jack terminals of said telephone 45 lines, wiping contacts in said Y-switches forming terminals of said trunks; switch plugs adapted to connect with said multiple jacks and forming terminals for said trunks at the ends distant from the wiping-contact 50 terminals thereof; means for placing a busy-test condition upon the terminals of a telephone line by connection of trunk wiping contacts with any set of waiting contacts of that line; means for placing busy-test conditions upon the terminals of a telephone 55 line by connection of a trunk plug with any jack of that line, motor mechanism for causing said wiping contacts to pass from set to set of said waiting contacts, and means for 60 causing the operation of said motor mechanism, said means becoming operable when the wiping contacts of a non-busy trunk rest in contact with waiting contacts of a non-busy line and said line has busy test 65 conditions placed upon its terminals by rea-

son of that line being connected with at some one of its multiplied terminals, either by wiping contacts or by a switching plug.

2. In a telephone system, a Y-switch, a trunk terminating in the wipers of said Y-switch, lines terminating in waiting contacts in said Y-switch, means for placing busy test conditions upon the waiting contacts of one of said telephone lines, motor mechanism for said wipers, and means causing said motor mechanism to become active when busy test is placed upon the waiting contacts of a line with which the wipers of a trunk are in electrical connection, substantially as described. 75

3. In a telephone system, a telephone line, a line relay responsive to current changes in said line when calling, a plurality of trunks, automatic rotary Y-switches, one associated with each of said trunks, each adapted to connect its associated trunk to said telephone line when said telephone line is calling; an auxiliary relay associated with each Y-switch and a circuit adapted to be closed by control of the substation upon the line relay 80 of said telephone line and extending through contacts of the auxiliary relay to the first of said Y-switches, whereby, when said circuit is closed by the control of said telephone substation, said first of said Y-switches will 85 respond and connect its associated trunk to said telephone line; said auxiliary switch operating when said Y-switch connects with the telephone line, to connect said circuit to the second of the Y-switches, substantially 90 as described. 95

4. In a telephone system, a telephone line, a plurality of rotary Y-switches, a circuit adapted to be closed by control of said telephone line and extending to the first of said Y-switches, and a relay in the first of said Y-switches to extend such circuit to the second of said Y-switches, and a circuit including the winding of said relay and extending through the line contacts of said 105 automatic Y-switch and thence closed through the substation bridge of said line, when said first Y-switch has its wipers in connection with the waiting contacts of said line, substantially as described. 110

5. In a telephone system, a plurality of telephone lines, a plurality of line relays each associated with and adapted to be energized by closure of one of said telephone lines, a plurality of rotary Y-switches in 120 each of which said telephone lines are connected to waiting contacts, a circuit adapted to be closed by control of the line relay becoming energized in response to a call from a substation upon any of said telephone lines 125 and extending to the first of said Y-switches, and a relay in the first of said Y-switches to extend said circuit to the second of said Y-switches when said first Y-switch has its wipers in connection with the waiting con- 130

tacts of a busy telephone line, substantially as described.

6. In a telephone system, a plurality of telephone lines, a plurality of trunks, Y-switches, one associated with each of said trunks, and each adapted to connect its associated trunk to a calling one of said telephone lines, line relays associated with said telephone lines, each adapted to become energized when its associated line circuit is closed in initiating a call, an auxiliary switching relay associated with each Y-switch and containing make and break contacts, and a motor circuit connected in multiple to contacts of said line relays, and thence to the shifting member of the make and break contacts in one of the said auxiliary switching relays, with a branch motor circuit extending from the normally closed 10 or "break" side of said relay contacts to the associated Y-switches, and a second branch extending from the normally open or "make" side of said contacts to the auxiliary relay of another Y-switch, whereby 15 when any line is calling said motor circuit will be closed by the line relay contact of the calling line causing the motor mechanism of the first Y-switch to operate, and means to energize the auxiliary relay of said 20 switch when the line is found to break the normally closed motor contacts and close the normally open contacts so as to shift the motor circuit to the next switch.

7. In a telephone system, a plurality of telephone lines, a plurality of trunks; Y-switches, one associated with each of said trunks and each adapted to connect its associated trunk to a calling one of said telephone lines, line relays associated with said 25 telephone lines, each becoming energized when its associated line circuit is closed, a motor circuit extending from a predetermined Y-switch and branching in multiple to contacts of said line relays, whereby, 30 when any line is calling said motor circuit will be closed by a line relay contact of the calling line causing the motor mechanism of the predetermined Y-switch to operate, and a relay in the operating Y-switch to extend

said motor circuit to the motor mechanism 50 of another Y-switch when the operating Y-switch connects with the calling line, substantially as described.

8. In a telephone system, a plurality of telephone lines, a plurality of trunks; Y-switches, one associated with each of said trunks and each adapted to connect its associated trunk to a calling one of said telephone lines, line relays associated with said telephone lines, each becoming energized 60 when its associated line circuit is closed, a motor circuit extending from one of said Y-switches and branching in multiple to contacts of said line relays, whereby, when any line is calling said motor circuit will be 65 closed by a line relay contact of the calling line causing the motor mechanism of said Y-switch to operate, and a relay in each Y-switch for removing its motor mechanism from said motor circuit when the Y-switch 70 is busy, substantially as described.

9. In an exchange system, the combination with telephone lines and cord circuits for connecting the same, of a plurality of switching mechanisms associated with the 75 cord circuits, the telephone lines being joined to a plurality of switching mechanisms, a relay included in each line and aiding in the control of any one of the plurality of switching mechanisms to which the 80 line is joined, and a transfer relay individual to each switching mechanism and being controlled by the connection through its switching mechanism of a cord circuit with an originating line, the transfer relay upon 85 operation serving to shift the capability of control by the relays of other lines terminating at its switching mechanism to other switching mechanisms, substantially as described and for the purposes set forth. 90

Signed by us at Grand Rapids, county of Kent and State of Michigan, in the presence of two witnesses.
